FLOYD KARKER RICHTMYER, OF ITHACA, NEW YORK

ELECTRON DISCHARGE DEVICE

Application filed July 29, 1924. Serial No. 728,831.

This invention relates to an electron discharge device and more particularly, to a device of the evacuated or gas-filled type designed for the detection or amplification of electrical energy.

In the construction of radio tubes or other electron discharge devices, it is desirable to obtain the maximum mutual conductance, with a given amplification constant, to reduce the plate resistance or space current effect to a minimum and to provide as large an electron-emitting surface for the cathode as is possible. The plate resistance may be decreased by decreasing the average distance from the anode to the cathode. This may be accomplished by using a cylindrical anode or plate mounted concentrically with respect to the cathode and relatively close thereto. The electron-emitting surface of the cathode may be increased by increasing the length of the cathode. However, because of inherent structural limitations in tubes of this type, the cathode or filament cannot exceed a certain length. This difficulty can be obviated however, by using a plurality of filament sections, the combined length of which is relatively long.

One of the objects of the invention is to provide an electron discharge device having a relatively long cathode in which the mutual conductance is a maximum for a given amplification constant.

Another object is to provide a discharge device, the cathode of which has a large electron-emitting area and in which the average distance between the anode and cathode is relatively small.

Another object is to provide a single radio tube which will perform a plurality of functions heretofore requiring separate tubes.

Another object is to provide a radio tube of simple construction which will be efficient and reliable in operation and which will have a long life.

Other objects and advantages will herein-after appear.

In accordance with this invention, the electron discharge device is constructed with a plurality of sets of electrodes. Each set may comprise a cathode, a surrounding grid or

control electrode and an anode encircling the grid and cathode. The cathode is preferably in the form of a linear filament and the grid and plate are, in the preferred form, cylindrical and arranged relatively close to the filament and to each other whereby the distance between the filament and plate is substantially constant for each part of the plate and relatively short. By using a plurality of anodes and control electrodes, it is possible to use several filament sections, the combined length of which is relatively long, thus giving a comparatively large effective electron-emitting area. By using a relatively long filament, a suitable electron-emission may be obtained at relatively low temperature, thereby prolonging the life of the device.

The corresponding electrodes of each set, may be connected in parallel although if desired, the filament sections may be operated in series and the grids provided with independent leads, whereby one set of electrodes for instance may be used for detection of radio signals and the other set for amplification thereof.

While an electron discharge device having but two sets of electrodes is shown and described herein, it is obvious that any other number might equally well be provided.

In order that this invention may be more fully understood, reference will be had to the accompanying drawings in which,

Fig. 1 is a perspective view of a mount for a radio tube embodying this invention;

Fig. 2 is a perspective view of the modified form of mount; and,

Fig. 3 is a section on the line III-III of Fig. 2.

The modification shown in Fig. 1 comprises a stem 1, a pair of anodes 2 and 3, a pair of grids or control electrodes 4 and 5 and a pair of cathode sections 6 and 7. The anodes 2 and 3 are preferably cylindrical in form and arranged concentrically with respect to the cathode in order to obtain a minimum average anode-cathode spacing. The anode 2 is supported by and joined to the anode 3 in parallel relation by straps or webs 8 which may be integral with the anodes or formed separately and welded or otherwise secured

thereto. The anode 3 is supported from the stem by the conducting support wire 9 to which it is secured by projections 10 formed on the outer side thereof and bent around 5 or welded to the support. The supporting wire 9 is sealed in the press of the stem 1 and may be joined to or form a continuation of the leading-in wire 12.

The grids or control electrodes 4 and 5 are 10 arranged within the anode or plates 2 and 3 respectively, and are of similar shape. These control electrodes may be supported at the lower end by divergent arms 13 and 14 of the supporting lead 15 sealed into the 15 stem and at the upper ends, they may be connected by a bridging member 16 which may be supported from the upper web 8 by a wire 17 insulated from the cross piece 16 by a glass bead 18 or other suitable means. 20 The grid supporting wire 15 is connected to or forms a continuation of the leading-in wire 24.

The filament sections 6 and 7 pass axially through the grid and anode and are connected 25 at their lower ends to the leading-in wires 19 and 20 respectively. Their upper ends are preferably joined by a connecting bar or bridging member 21, resiliently supported by a hook 22 carried at the upper end of a supporting wire 23, sealed into the stem press of the device.

In the modifications shown in Figs. 2 and 3, the plates 2 and 3 are formed from a single sheet of metal bent to the form of a 30 figure 8. These plates are supported at their mid portion by a single central supporting lead 25 welded or otherwise suitably secured thereto. In this embodiment of the invention, the upper end of the filament sections 6 and 7 are supported from the horizontal arm 26 of the supporting conductor 27. Each 35 of the grids 28 and 29 are supported by independent conductors 30 and 31 joined to or forming continuations of the leading-in wires 32 and 33. This form of tube is particularly adapted for actual use, it being capable of serving simultaneously as a detector and amplifier or for both radio and 40 audio frequency amplification, by suitably connecting the independent grids in independent circuits in the radio receiving apparatus, as disclosed, for example, in Fig. 2. The arrangement of the electrodes otherwise is substantially the same as shown in Fig. 1. 45 Obviously, this invention is not limited to the specific embodiments shown and described herein but is susceptible of many modifications and variations without departing therefrom.

50 What is claimed is:

1. In a vacuum-tube device, a member of sheet material of S-shaped cross-section providing two connected cylindrical portions and means whereby each cylindrical portion constitutes an anode.

2. An electron-discharge device comprising a pair of cylindrical anodes forming an integral metallic structure electrically interconnected in said device, a grid, and an electron-emitting cathode disposed inside each anode, said cathodes being electrically connected and said grids being electrically separate.

3. In combination with an electron tube having an electrically unitary cathode, an electrically unitary anode and a plurality of electrically independent grids, means for impressing independent E. M. F.'s on said grids.

4. In combination with an electrical system comprising a plurality of circuits, an electron tube having an anode comprising a unitary structure, an electrically unitary cathode and a plurality of grids, and means for impressing E. M. F.'s derived from different members of said plurality of circuits on different grids.

5. In combination with a radio receiving system comprising circuits of different frequencies and an electron tube having a unitary anode, a unitary cathode and separate grids, means for impressing a periodic E. M. F. derived from a circuit of one of said frequencies on one grid and for impressing a periodic E. M. F. derived from a circuit of another of said frequencies on another grid.

6. An electrical-discharge device having a single anode comprising two parallel cylindrical portions, a cathode and a control electrode within each of said cylindrical portions, said cathodes being electrically connected within said discharge device, and said control electrodes being without electrical connection within said discharge device.

7. An electrical-discharge device having a single anode comprising cylindrical portions which are mechanically and electrically connected together by means of metallic members, a cathode member having a portion within each of said cylindrical portions and a control electrode within each of said cylindrical portions.

In testimony whereof, I have hereunto subscribed my name this 22d day of July, 1924.

FLOYD KARKER RICHTMYER.
